COLLAPSIBLE SUIT AND TROUSER HANGER

Mathias W. Boyd, Oakland, Calif.

Application August 6, 1948, Serial No. 42,893

5 Claims. (Cl. 223—89)

1

This invention relates to suit and trouser hangers and particularly to a type of collapsible or knockdown hanger for suits and trousers, which may be conveniently taken apart and reassembled at will.

The main object of my invention is to provide a collapsible combined suit and trouser hanger which serves to support a coat and two or more pairs of trousers or suit skirts, and yet may be taken apart to occupy a minimum of space in a traveling bag or luggage.

Another object is to provide a hanger of the indicated character which has a pair of interconnected center or nucleus blocks which form a nucleus for the hanger structure, to one of which blocks the main hanger members are detachably secured during use.

A further object is to have such a hanger in which two interconnected nucleus blocks are spaced apart, one above the other, with the lower block provided with a pair of rods extending in opposite directions therefrom and projecting detachably into the main hanger members.

It is also an object to provide a hanger of this type with trouser or skirt engaging members or triggers slidably mounted on the oppositely extending pair of rods with springs on the latter biasing these members apart to bring them into engagement with any size of trouser or skirt to be supported thereby.

It is even an object of the invention to have a hanger of the mentioned type in which it is readily possible to increase the capacity for hanging trousers or skirts thereon.

A practical object is, of course, to make a combined collapsible suit and trouser hanger of readily available materials, and durable form and at reasonable cost.

Further objects and advantages of my invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a front elevation of a combined collapsible suit and trouser hanger made according to the invention and embodying the same in a practical form.

Figure 2 is a section taken on line 2—2 in Figure 1.

Figure 3 is another section taken on line 3—3 of Figure 1.

Figure 4 is a plan view of an attachment adapt-

2

ed to be mounted upon the hanger of Figure 1, and made according to certain of the principles of the invention.

Figure 5 is a section taken on line 5—5 of Figure 4.

Throughout the views, the same reference numerals indicate the same or like parts.

When traveling in business and also for pleasure, it is frequently desirable to have presentable clothes to use at various engagements and appointments, etc., and at the hotels and the like, at which the traveler arrives, it is immediately desirable upon arrival to be in a position to hang up the garments brought along in order to have them available in fine condition at any time. In all too many cases, good hangers are not available, especially for trousers and suit skirts, and proper hangers therefor of conventional types are so wasteful of space that it is out of the question to bring them with the clothes in the traveling bags or suitcases used.

After carefully considering this problem, it has occurred to me that a hanger should be made collapsible and also combined with special trouser hanger means so that several ends are served by the hanger to make it convenient and useful to the greatest possible degree. Upon following out this problem, I have succeeded in producing a hanger of the mentioned type which plausibly serves the foregoing objects and avoids the mentioned disadvantages, as will now be set forth in detail.

Hence, in the practice of my invention and referring again to the drawing, a hanger generally indicated at 6, primarily includes a center block 7 having a vertically extending hook shank 8 terminating above the block in a suspension hook 9, and at the lower end having a threaded portion 10 screwed into a connector 11, whose purpose will be explained further on. Projecting from the opposite sides 12, 12 of blocks 7 are a pair of short studs 13, 13 projecting detachably into corresponding recess portions 14, 14 in the inner ends 15, 15 of a pair of main hanger members 16, 16 while spaced above the studs 13, 13 are a pair of outwardly extending yokes 17, 17 which normally envelop the upwardly projecting neck portions 18, 18 of the hanger member 16, 16 while the yoke members at the outer ends thereof are seated in slots 19, 19 in the upper portions of said hanger members.

To the lower end of the connector 11, previously mentioned, is connected as by screwing the upper threaded end 20, a suspension rod 21 extending upwardly through a block 22, the rod 21

having a head 23 below the block and a washer 24 which prevents the block from dropping off this rod, while the block itself has the lower front and rear portions 25, 25 cut arcuately inward to present the lower end 26 narrow and almost wedge-shaped for a purpose that will presently appear. Into the opposite ends 27, 27 of block 22 are screwed a pair of aligned rods 28, 28 having a pair of compression springs 29, 29 mounted thereon, the rods extending at their outer ends detachably into a pair of metal cups 30, 30 fitted into the inner sides 31, 31 of the outer lower ends of hanger members 16, 16, the mentioned cups 30, 30 being held in place by screws 32, 32 inserted from the outer sides of the hanger members.

Slidably mounted upon the rods 28, 28 beyond the outer ends of the springs 29, 29 are a pair of trouser or skirt engaging members or triggers 33, 33, each including a pair of pendent trouser-engaging lugs 34, 34 spaced apart upon each member 33. The arrangement is such that a pair of trousers or a suit skirt may be engaged upon the interior thereof by means of one member 34 upon one trigger member or block 33 and a corresponding engaging member 34 upon the other block, with the springs biasing the trigger blocks 33, 33 apart in such fashion as to hold the trousers or skirt in place upon the pendent members 34, 34 across the front or rear of block 22, which however clears the garment by virtue of the cut portions 25, 25 on the opposite sides of the lower portions thereof. Due to the presence of two engagement members 34 upon each trigger block 33, it is obvious that two pairs of trousers may be accommodated upon the hanger, one before and one behind the block 22. Although the members 17 in Figure 1 are described as yokes, these members could also be formed of a pair of opposite hooks 35, 35 screwed into the opposite ends 12, 12 of block 7 with their outer ends bent toward each other to form retaining hooks 36, 36 engaging in slots 19, 19 and holding the upper neck portions 18, 18 of main hanger members 16, 16 in place against the center block 7, as especially shown in Figure 3.

Upon occasion, it may be desired to hang up more than two pair of trousers, while using the same hanger 6, and for this purpose the lower nucleus block 22 is provided upon its forward and rear surfaces 37, 37 with a pair of right-angle hooks 38, 38 which are screwed into the block 22 so that the hook portions project a small distance from the surfaces 37 to form supports for an auxiliary trouser or skirt hanger, as will now be explained.

A further nucleus block 42 has a rod 43 extending longitudinally therethrough and at the ends of this rod are mounted a pair of further slideable trigger blocks 44, 44 provided with depending trouser-engaging members 45, 45 adapted to engage in the trousers or suit skirts within the edges thereof, as in the case of the previously explained use of trouser-engaging members 34, 34, the center block 42 having the lower front and rear cut-out portions 46, 46 to clear the garments on both sides of this block. Upon the rod 43, at each side of block 42, are mounted a pair of expansion springs 47, 47 terminating at the outer ends in heads 48, 48 with washers 49, 49 limiting the outward movement of blocks 44 and preventing accidental loss thereof from the rod, the springs engaging against the inner ends of the mentioned blocks in order to bias them apart, 75

as in the case of springs 29, 29 operating against the trigger blocks 33, 33 previously described.

Projecting from the front and rear sides 50, 50 of the center block 42 are a pair of outwardly and downwardly directed attachment hooks 51, 51 adapted to engage within the hooks 38 on block 22 of the hanger, as particularly noted in Figure 3, wherein it may be seen that the block 42 is thereby attached directly in front of or 10 could be attached directly rearwardly of block 22 of the hanger by the mentioned interengagement of the hooks 51 with the hooks 38 thereof. The mentioned block 42 is instantly detachable from block 22 by merely lifting the hooks 51 thereof from engagement with the hooks 38 and this block with its two trigger blocks 44 is instantly free and independent until again hung up on the block 22 in the manner described. It is self-evident that a pair of auxiliary trouser hangers, similar to that shown in Figures 4 and 5 and in broken lines in Figure 3, may be used both fore 20 and aft of the nucleus block 22 so that six pairs of trousers may be hung up if desired.

In order to collapse the hanger of Figures 1 25 and 2, which is also shown in section in Figure 3, the first step is to pull the outer ends 31, 31 of the main hanger members 16 apart in order to release the outer ends of rods 28, 28 from sockets 38 so that the upper ends of the neck 30 portions 18, 18, which are rounded for this purpose, will ride against the sides 12, 12 of the center or nucleus block 7 while withdrawing the studs 13, 13 from recesses 14, 14, the outer ends 35 of the hanger members meanwhile describing upwardly and outwardly sweeping arcs until the neck portions 18, 18 are free from the yokes 17, 17. Thereafter the hook shank 8 may be 40 unscrewed from connector 11 and the hanger has been reduced to the elongated rod portions 28, 28 connected to block 22 with the trigger blocks 33, 33 thereon and the rod 21 with its head 23 and the connector 11 thereon together forming one unit, the block 7 with the yokes 17, 17 forming a second unit, with the hook 9 while the 45 main hanger members 16, 16 alone form two additional units, all these units being readily laid together in a compact space or scattered through the contents of a traveling bag or suitcase in a manner which would never be possible 50 with a complete hanger.

It has been mentioned that the yokes 17, 17 may be divided into separate hooks 35, 35 with the hook members 36, 36. In like manner, the hooks 38, 38 could be united to form yoke members 55 projecting into block 22 and the same could well be true of the hooks 51, 51 of block 42.

The blocks 7, 22 and 42 may be of wood, plastic or any suitable material, and particularly if of plastic the studs 13, yokes 17 or shanks 35 60 of the hook members 36 in the case of block 7 or the hooks 38 or the yokes substituted therefor in block 22, as well as hooks 51 or the yokes substituting therefor in block 42, may all be embedded in the block by molding the same in place, if so desired, and the trigger blocks 33 and 44 with their pendant trouser or skirt engaging members 34 or 45 may be made of wood or plastic and entirely integral if so desired, while the main hanger members 16, 16 may also be of 65 wood, plastic or any other material that will serve the purpose, and in fact all the mentioned members may also be of aluminum or a light alloy instead of wood or plastic, while the rods 28, 43 and short rods 21 and shank 8 with its hook 9, as well as all the mentioned hooks and

yokes may be made of stainless steel, aluminum or any alloy that will serve the purpose and therefore are not limited to any particular material with regard to any of the mentioned parts and I am free to use any natural composition or substance that will serve the purpose best in my own estimation.

Manifestly, variations may be resorted to and parts and features may be modified or used without others within the scope of the appended claims.

Having now fully described my invention, I claim:

1. A collapsible combined suit and trouser hanger including a pair of main hanger members normally projecting outwardly and downwardly in opposite directions and terminating in downwardly directed ends, a common connecting means detachably interconnecting the inner adjacent ends of the hanger members, said last named means including a center block having a pair of studs projecting outwardly in opposite directions and extending detachably into corresponding recesses in the inner adjacent ends of the hanger members, a suspension hook projecting upwardly from said center block, elongated rod means extending at both outer ends detachably into receiving sockets in the inner sides of said downwardly directed ends of the hanger members, a pair of slidable trouser-engaging members mounted on the rod means, further means connecting the intermediate portion of the latter with the common connecting means to retain said rod means assembled with said hanger members, and compression spring means mounted on said rod means between said slideable trouser-engaging means to bias them apart.

2. A collapsible combined suit and trouser hanger including a pair of main hanger members normally projecting outwardly and downwardly in opposite directions and terminating in downwardly directed ends, a center block having a pair of studs projecting outwardly in opposite directions extending detachably into corresponding recesses in the inner adjacent ends of the hanger members, a suspension hook projecting upwardly from the center block, a pair of yokes projecting rigidly outwardly from the latter above the studs and at their outer portions engaging in upwardly open slots in the upper portions of said hanger members, a second center block disposed beneath and connected to the first-mentioned center block, a pair of aligned rods extending rigidly in opposite directions from the second center block beneath the hanger members with the outer ends thereof extending detachably into a pair of receiving sockets in the inner sides of said downwardly directed ends of said hanger members, a trigger block slidably mounted on each rod having at least one depending trouser-engaging member fixed thereon, and a compression spring mounted on each rod between the trigger block thereon and said second center block.

3. A collapsible combined suit and trouser hanger including a pair of main hanger members normally projecting outwardly and downwardly in opposite directions and terminating in downwardly directed ends, the hanger members having transverse upwardly open slots spaced from the inner ends thereof forming neck portions thereon, a center block having a pair of studs projecting outwardly in opposite directions extending detachably into corresponding recesses in the inner adjacent ends of the hanger members, a pair of retaining hooks projecting rigidly out-

wardly from each of the two opposite ends of the center block above said studs and extending upon opposite sides of the neck portions with the hook portions engaging in said upwardly open slots, 5 the upper inner ends of said neck portions being rounded to facilitate disengagement of said hanger members from said studs and retaining hooks, a second center block disposed beneath the first-mentioned center block and having the lower forward and rear portions cut back arcuately to provide clearance portions thereon, a pair of aligned rods extending rigidly in opposite directions from the second center block beneath the hanger members with the outer ends thereof extending detachably into a pair of receiving sockets in the inner sides of said downwardly directed ends of said hanger members, a trigger block slidably mounted on each rod having a pair of depending trouser-engaging members spaced apart thereon, 10 a suspension hook projecting above the top of the first-mentioned center block and having a shank extending down through the latter, a rod having a head at the lower end thereof and extending upwardly through the second center block, and a detachable connector interconnecting the lower end of said shank and the upper end of the upwardly extending rod.

4. A collapsible combined suit and trouser hanger including a pair of main hanger members normally projecting outwardly and downwardly in opposite directions and terminating in downwardly directed ends, the hanger members having transverse upwardly open slots spaced from the inner ends thereof forming neck portions thereon, a center block having a pair of studs projecting outwardly in opposite directions extending detachably into corresponding recesses in the inner adjacent ends of the hanger members, a pair of retaining hooks projecting rigidly outwardly from each of the two opposite ends of the center block above said studs and extending upon opposite sides of the neck portions with the hook portions engaging in said upwardly open slots, the upper inner ends of said neck portions being rounded to facilitate disengagement of said hanger members from said studs and retaining hooks, 30 a second center block disposed beneath the first-mentioned center block and having the lower forward and rear portions cut back arcuately to provide clearance portions thereon, a pair of aligned rods extending rigidly in opposite directions from the second center block beneath the hanger members with the outer ends thereof extending detachably into a pair of receiving sockets in the inner sides of said downwardly directed ends of said hanger members, a trigger block slidably mounted on each rod having a pair of depending trouser-engaging members spaced apart thereon, a suspension hook projecting above the top of the first-mentioned center block and having a shank extending down through the latter, a rod having a head at the lower end thereof and extending upwardly through the second center block, 35 a connector interconnecting the lower end of said shank and the upper end of the upwardly extending rod, a pair of hook members projecting from each of the forward and rear sides of said second center block above the cut back clearance portions thereof with the hooked ends directed horizontally toward each other, and an auxiliary trouser hanger adapted to be attached to the latter hooks on the forward or rear sides of said second center block, including a further center block having a pair of attachment hooks rigid 40 upon each of the forward and rear sides thereof.

terminating in downwardly directed hook portions adapted to interengage with the hooks on said second center block, a rod extending through the ends of the further center block having terminal heads upon the ends thereof, a pair of trigger blocks slidably mounted on the last-mentioned rods within the heads thereof and having a pair of pendant trouser-engaging members fixed upon each, and a pair of compression springs mounted on the latter rod between said last-mentioned trigger blocks and said further center block.

5. A combined suit and trouser hanger including a pair of main hanger members connected together with a suspension hook projecting upwardly from between them, elongated rod means interconnecting the inner portions of the lower outer ends of the hanger members, a center block mounted intermediately upon said rod means having hook members projecting from each of the front and rear sides thereof, a slidably adjustable means on said rod member for engaging with and supporting at least one pair of trousers, and an auxiliary trouser hanger adapted to be attached to the latter hooks on the forward or rear side of said first-mentioned center block, including a

10

15
